CLAIM

The ornamental design for a cabinet for electronic components, as shown and described.

DESCRIPTION

FIG. 1 is a perspective view of a cabinet for electronic components showing the design;

FIG. 2 is a plan view of a front side thereof;

FIG. 3 is a plan view of a right side thereof;

FIG. 4 is a plan view of a left side thereof;

FIG. 5 is a plan view of a rear side thereof; and

FIG. 6 is a plan view of a top side thereof; and,

FIG. 7 is a plan view of one of the forty-two horizontal vent grill shown in FIGS. 1 and 2.

The plan views of FIGS. 2–6 are enlarged relative to the perspective view of FIG. 1.

The plan view of FIG. 7 is enlarged relative to the plan views of FIGS. 2–6.
